UNITED STATES PATENT OFFICE.

CHARLES E. SNAPP, OF GROTTIES, VIRGINIA.

COIN-CONTROLLED VENDING-MACHINE.

SPECIFICATION forming part of Letters Patent No. 606,249, dated June 28, 1898.

Application filed September 7, 1897. Serial No. 650,802. (No model.)

To all whom it may concern:

Be it known that I, CHARLES E. SNAPP, of Grottoes, in the county of Rockingham and State of Virginia, have invented a new and 5 useful Improvement in Vending-Machines, of which the following is a specification.

My invention is an improvement in the class of coin-controlled machines adapted for delivering cigars individually or in pairs; also 10 packages of cigarettes and other articles, automatically when certain trip mechanism is operated by a coin of the proper denomination.

My improved machine is so constructed as to be particularly efficient in preventing its 15 surreptitious operation, as by use of any coin other than the proper one or of any substitute therefor, such as lead or other soft and hard metal disks. The machine is at the same time comparatively simple in construction 20 and operates with ease and certainty in the delivery of cigars, cigarette-boxes, or other articles for which it is adapted.

The details of construction are hereinafter described with reference to accompanying 25 drawings, four sheets, in which—

Figure 1 is a perspective view of my machine. Fig. 2 is a perspective view of the push-bar or coin-carrier. Fig. 3, Sheet 2, is a 30 vertical section of the machine. Fig. 4 is a horizontal section on line 4-4 of Fig. 3. Fig. 5, Sheet 3, is a horizontal section on line 5-5 of Fig. 3. Fig. 6 is a perspective view showing a portion of the case with coin-chute and a portion of the lever mechanism. Fig. 7 is 35 a perspective view of the magnet and attachments thereof. Fig. 8 is a perspective view of the interior mechanism. Figs. 9 and 10, Sheet 4, are vertical sections of the interior mechanism, illustrating different stages in 40 the operation of the same. Fig. 11 is a side view of a modification of the tilting table. Fig. 12 is a front view of the coin-chute and coin-operated levers connected therewith. Fig. 13 is a perspective view of the lever-ejector 45 for lead disks, &c.

The case inclosing the operative parts has the form usual in this class of machines, being composed of an enlarged rectangular base A, an extended top or vertical portion A', and 50 the inclined front a, in which the mouths of the coin-chutes 1 are located.

In practice I propose to employ one or more complete coin-controlled mechanisms in the same case. In Fig. 1 I illustrate the case adapted for three such mechanisms, one being for delivery of a single cigar, another for delivery of two cigars, and the third for a package of cigarettes or other articles. I will first describe the invention as adapted for delivery of cigars singly and then indicate the 60 slight change of certain parts required to allow delivery of two or more cigars simultaneously, also of cigarette and other packages.

When the nickel enters a coin-chute 1, it operates mechanism that allows release of one 65 or more cigars, as will be presently described.

The chute 1 is shown arranged at an angle of forty-five degrees and delivers the coin—say a nickel—into a transverse slot 2, formed in the boss of a flat bar 3, that slides on the horizontal 70 skeleton plate or diaphragm 4, arranged in the upper portion of the base A of the case and is operated—i.e., reciprocated—by a push-rod 5, that projects from the front of the base. Said bar 3 has lateral arms 6; Fig. 2, having 75 parallel rods 7, to which spiral retracting-springs 8 are applied, as shown. The aforesaid slot is large enough to allow the nickel to pass through the transverse slot 9 in the plate 4 and into the coin-receptacle 10 below, when 80 the bar 3 is slid to carry it back to the proper place. When the slideable bar 3 is pushed back, as shown in Fig. 10, the coin is supported by and rides on the depressed trough-like portion 11, Figs. 9 and 10, of the plate 4, 85 and is thus prevented from falling prematurely out of the slot 2 in the bar. Just before the coin reaches the discharge-slot 9 in the plate 4 its upper edge strikes against and slides under the upcurved end of a lever-arm 90 12, that projects from a tiltable table 13, which is pivoted at its ends in suitable angular arms or lugs 14, as shown. The said table 13 is arranged parallel to the rear edge of the plate 4 and directly beneath the vertical passage 95 15, in which the cigars to be delivered are contained, the same lying one upon another horizontally. When the coin thus rides under the curved trip-arm 12, the latter is raised, and then the rear end of bar 3 comes in contact with the semicircular pendent portion 12^a of the trip-arm, and thus continues to tilt the 100

table 13, as shown by full lines, Fig. 9, so as to effect the discharge of the cigar that had been deposited thereon a moment before. Simultaneously with such discharge the coin 5 drops from the slot 2 in bar 3 through the coincident slot 9 in plate 4 and passes into receptacle 10, as already stated. When the cigar leaves the tilting table 13, it passes into and rolls down the curved delivery-chute 16, and 10 thus becomes visible and accessible to the customer at the front end of said chute. In such discharge the cigar passes back through a transverse opening 17 in the rear wall of the reservoir-passage 15, which opening is closed. 15 by a door or flat valve 18, Fig. 9, which extends transversely in a vertical plane and is hinged to the rear wall of the reservoir-passage just above said opening 17 and opposite the tilting table 13. A spring 19 holds the 20 valve normally closed, and it is opened by engagement of a rigid cam 20, fixed vertically on the table 13. Thus when the latter tilts said cam 20 presses against the valve 18 and forces it open, so that the cigar previously 25 deposited on the table may roll off into the chute 16. It will be understood that the function of valve 18 is to prevent the cigar passing off the table 13 prematurely.

The mechanism operated by the coin upon 30 entering the chute 1 and which allows delivery of a cigar upon the table 13 is constructed and operates as follows:

Two like levers 21, Figs. 9 and 12, are pivoted centrally in a vertical plane and opposite each other below the coin-chute 1, and their upper beveled and hook-like ends 22 are bent at an obtuse angle, Fig. 9, and project into opposite slots formed in the sides of the chute 1 at a point adjacent to its mouth. 35 The lower ends of said levers 21 are provided with holes to receive the front ends of horizontal levers 23, that are pivoted to a plate 24, arranged above and parallel to the main plate 4, before referred to. The inner or rear 40 ends of such levers 23 project beneath the reservoir-passage 15, Fig. 9, being thus located at the lateral extremities of the latter. A coil-spring 25, Fig. 6, serves to connect the 45 said levers 23 at a point between their pivots and the reservoir-passage 15, so that their rear ends are normally held approximately or in 50 due position to support a cigar, as shown in Fig. 9. It will now be apparent that when a nickel is introduced into the chute 1 it must 55 pass between the beveled ends 22 of the levers 21 and in so doing force them apart and thereby draw the outer or front ends of the horizontal levers 23 toward each other, which causes corresponding separation of the rear 60 ends of the same, so that the cigar resting thereon, being no longer supported, falls upon the table 13 and is then disposed of, as before described. The spring 25, connecting the levers 23, retracts them to their normal position 65 the instant the coin passes the upper ends 22 of the levers 21, and said levers 23 thus re-

sume their function of supporting the series of cigars in the reservoir 15; but as a supplemental means for this purpose I provide the table 13 with curved guard-fingers 26, 70 Figs. 8 and 9, which when the table tilts rearward to discharge interpose beneath the next cigar of the series. These fingers are curved rearward from the front edge of the table and stand in a vertical plane. They are 75 formed of material which is flexible, yet sufficiently rigid to enable them to retain under the ordinary conditions of use any curve to which they may be bent. They are thus adapted to be so bent and adjusted that their 80 free ends will be higher or lower, as required to allow discharge of two cigars or one, as the case may be.

The means for preventing operation of the machine by a disk of steel or iron of the same 85 diameter as a nickel is the permanent magnet 27, Figs. 7, 9, and 10, which is pivoted on vertical lugs 28 of the main plate 4, which lugs also serve as stops to support the front end of the magnet when thrown down by the 90 springs 28^a, Figs. 7, 8, and 9, so that the magnet is held normally in horizontal position. The slideable bar 3 has a cam-lug 29, Figs. 9 and 10, which is so arranged as to strike the lug 30, pendent from the front end of the magnet, and tilt the latter so that its rear end is 95 carried down into contact with or at least into close proximity to the coin or spurious disk being carried backward in the slot 2 of the bar 3. A disk capable of magnetic attraction 100 will be lifted out of the slot 2 and snapped off the magnet as the latter resumes its former position. This action is due to the retractive action of springs 28^a, which are coiled about the pivot or axle of the magnet, and the form 105 of the lugs 29 and 30 one side of which is vertical. The magnet-lug 30 is pivoted to allow it to pass back over lug 29 when the push-bar is retracted. The bar 3 has two other fixed lugs 110 or wipers 29^a, Figs. 2, 9, and 10, which serve to push off from the magnet any adhering iron or steel disk that may fail to be snapped off when the magnet is thrown back, as above described.

The means for preventing a spurious soft-metal disk from operating the machine are 115 as follows:

A forked or bifurcated cam-lever 31, Fig. 13, is pivoted to and beneath the main plate 4 and supported normally in horizontal position by one or more springs 32. The rear end of the lever 31 is a projection 33, having a beveled upper edge, as shown in Figs. 3 and 13, and adapted to work in the coincident lengthwise slots 2 and 9 of bar 3 and plate 4. The 120 arms of said lever have cam projections 34 on the upper side, and the slideable bar 3 has two pivoted wipers 35, which are pendent in slots 36 of the plate 4 and suitably arranged to act on the cams of the bifurcated lever 31, 125 so as to depress the latter. Such depression occurs only when the bar 3 slides inward, since 130

the wipers 35 are then held vertical by engagement of their front shoulders 37 with lateral pins 38, fixed in the lugs 39, and when the bar 3 is retracted by its springs 8 the 5 wipers 35 tilt and merely drag back over the cams 34.

When a lead disk is delivered from the chute 1 into the slotted boss of bar 3 and the latter is pushed back, the disk strikes the 10 point of the trip-arm 12 of table 13 and is bent over frontward, as shown in Fig. 10, and then the wipers 35, which had previously depressed the forked lever 31, having at this time passed beyond the cams 34 the beveled head 33 of 15 the lever 31 is forced up through the slot 40 and, striking the disk, ejects it from the slot 2.

The trip-arm 12 has a lug 41, which subserves two purposes, namely: It projects laterally, Fig. 8, so as to bear on plate 4, and thus 20 support the table in normal position, and it also serves as a stop for the slideable bar 2 when carrying a soft-metal disk that fails to raise the trip-arm 12, as before described. Surreptitious operation of the machine is thus 25 prevented by simple but reliable means.

As shown in Fig. 3, the case A has a removable door 42, secured by a hasp-lock 43, and the adjacent rear side of the delivery-chute 16 has a hinged portion 44, that is supported 30 by the case-door 42, and thus adapted to open when the latter is removed. Thus access may be had to the lower side of the coin-receptacle 10, which has a hinged section 45, provided with parallel side flanges 46. The upper end 35 of such section 45 is secured by a button, hook, lock, or any other preferred form of fastening 47. The dotted lines, Fig. 3, indicate the open position of parts 44 and 45, as when it is desired to remove the cash from receptacle. 40 Having thus described the machine as adapted for vending cigars singly, it only remains to further state the following changes and modifications:

A cigar-box may be placed in the rear compartment 48 of the case A', as shown in Fig. 45 3, and its front side being removed the cigars will deliver themselves into the passage 15 as required. Said box may be supported by clips, brackets, or clamps.

To adapt the machine to vend two cigars simultaneously, the curved fingers 26, attached to the tilting table 13, are bent up or extended, so as to describe a larger arc, and thus cover the space equal to the aggregate diameter of 55 two cigars. In other words, the said fingers 26 are so curved as to enter between the second and third cigars of the series when the table tilts, and thus support all cigars above the second one. The horizontal levers 23, 60 supporting cigars, are also raised sufficiently to allow room for two cigars below or between them and tilting table 13.

In Fig. 11 I show a table 13^a, constructed flat to hold a cigarette-box, and the upper 65 side of the trip-arm 12^a has an arc-lug 50, which is described from the pivot of said arm as a

center, so that as the table tilts said lug will pass back under the second box and support all above the first while the latter is being discharged.

70

What I claim is—

1. In a vending-machine, the combination with the pivoted tiltable table, having the lever-arm projecting horizontally but curved upward, of a horizontal slide having a coin-holding slot or socket, and arranged in line with, but at a lower point than, said arm, and movable toward and from the latter, as shown and described.

75

2. In a vending-machine, the combination with a coin-chute and reservoir or compartment for holding cigars or other articles, of a tiltable table located below said compartment, a movable coin-carrier and lever mechanism adapted to be acted on by the coin in 85 passing through said chute, for releasing one or more cigars or other article, substantially as shown and described.

80

3. In a vending-machine, the combination with a tiltable table for temporarily holding 90 cigars or other articles, said table having a curved lever-arm, of a movable coin-carrier adapted to bring the coin into contact with said arm, for tripping the table, as shown and described.

95

4. In a vending-machine, the combination with the reservoir-passage and the coin-chute having side slots, of the pivoted levers having beveled ends that project into and normally lie in the chute-slots, the pivoted horizontal levers projecting into the reservoir-passage and having a loose connection with the first-named or coin-operated levers, a spring for holding both sets of levers in retracted position, as shown and described.

100

5. In a vending-machine, the combination of the slideable coin-carrier and device for supporting a cigar or other article to be sold, said device having a curved trip-arm whose base portion is curved to adapt it for sliding contact with the end of the coin-carrier, substantially as shown and described.

105

6. In a vending-machine, the combination with the reservoir-passage, a movable table or support for the articles to be sold, of a hinged valve for closing the opening at rear 110 of such support, and means connected with the support for acting on the valve to open the same, substantially as shown and described.

115

7. In a vending-machine, the combination with the reservoir-passage and the tiltable table arranged beneath it, and having a rigid arm or cam, of the hinged valve or plate hanging alongside the table, in such proximity as to adapt it to be acted on by said 120 cam, and a spring for holding the valve normally closed as shown and described.

125

8. In a vending-machine, the combination with the reservoir-passage, of the tiltable table arranged beneath the same, and having 130 curved fingers which are arranged in vertical planes and made of flexible material that ren-

ders them capable of retaining the form into which they may be bent, as shown and described.

9. In a vending-machine, the combination 5 of a tilttable magnet and a movable coin-carrier adapted to tilt the magnet when moved forward substantially as shown and described.

10. In a vending-machine, the combination 10 with the magnet pivoted horizontally and weighted at its front end, of the movable coin-carrier having a projection adapted to strike the magnet and tilt the same when moved inward as specified.

11. In a vending-machine, the combination 15 with a coin-carrier, of the magnet weighted at one end, lugs to which it is pivoted, said lugs having shoulders which support the magnet in normal position, as shown and described.

12. In a vending-machine, the combination 20 with the slotted, slidale coin - carrier of a

spring-actuated coin-ejector pivoted beneath the carrier, and having a portion which is adapted to project upward into the slot in the carrier, and means for depressing said ejector while the coin is being moved forward as 25 shown and described.

13. In a vending-machine, the combination 30 of a slotted slideable bar for carrying a coin, wipers pivoted to and pendent from such bar, a spring-supported lever arranged beneath the bar and having cam projections which the wipers act on when the bar is moved forward, said lever having a coin - ejecting portion which is adapted to enter the slot in said bar substantially as shown and described.
